UNITED STATES PATENT OFFICE.

EDWIN L. LLOYD, OF PHILADELPHIA, PENNSYLVANIA, ASSIGNOR TO THE JOLY STOPPER COMPANY, OF SAME PLACE.

BOTTLE-STOPPER.

SPECIFICATION forming part of Letters Patent No. 395,910, dated January 8, 1889.

Application filed June 25, 1888. Serial No. 278,127. (No model.)

To all whom it may concern:

Be it known that I, EDWIN L. LLOYD, a citizen of the United States, and a resident of Philadelphia, Pennsylvania, have invented 5 certain Improvements in Bottle-Stoppers, of which the following is a specification.

My invention relates, mainly, to that class of bottle-stoppers in which the sealing is effected by means of a flexible disk jammed 10 against the walls of the bottle-neck, one object of my invention being to prevent the accidental displacement or loosening of a stopper of this character, a further object being to cheapen the construction of the stopper, 15 and a still further object being to provide for the ready insertion of the stopper, the ready forcing of the same into the bottle to open the same, and the ready removal of the stopper from the bottle.

20 In the accompanying drawings, Figure 1 is a sectional view of part of a bottle with my improved stopper applied thereto. Fig. 2 is a similar view showing the mode of removing the stopper from the bottle. Fig. 3 is a perspective view of the parts of the stopper detached from each other, and Figs. 4 and 5 are views illustrating modified forms of the stopper.

25

As before remarked, my invention is directed mainly to that class of stoppers in which a flexible disk—preferably of rubber—is jammed in the neck of the bottle to close or seal the same, and one feature of my invention consists in combining with a stopper of 30 this character a locking device to engage with the flaring inner portion of the neck and prevent the accidental outward loosening or dislodgment of the stopper from the neck, the locking device, however, not interfering with 35 the ready forcing of the stopper into the bottle in the opening of the same, or with the ready removal of the stopper from the bottle in the proper way.

As shown in Fig. 1, the stopper consists of 40 a tubular shank, *a*, having at the upper end a sealing-disk, *b*, and at the lower end a locking-disk, *d*, the latter being of slightly greater diameter than the sealing-disk, and the whole being confined to a central rod or 45 stem, *f*, by washers *g* and *h*, the latter being interposed between the lower or locking disk,

d, and an eye, *m*, at the inner end of the stem *f*, while the washer *g* is interposed between the upper or sealing disk, *b*, and shoulders formed upon the stem *f* by flattening the same, as at *n*, at a point immediately above the washer.

When this stopper is driven into the neck of a bottle to the proper extent, as shown in Fig. 1, that portion of the upper or sealing disk, *b*, which projects beyond the washer *h* is bent upward and jammed firmly against the walls of the bottle-neck, while the lower disk, *d*, occupies such a position in the flaring lower portion of the neck of the bottle that it is free 60 to expand to its full extent and bears against said flaring walls of the neck, as shown. The lower washer, *h*, is of such diameter that the stopper cannot be withdrawn from the neck while occupying the position shown in Fig. 1, 65 as the projecting rim of the disk *d* will be jammed by the washer against the sides of the neck, and will thus serve as a lock to prevent upward movement of the stopper.

In opening the bottle the stopper is driven 70 down into the same, and in order to remove the stopper its position is reversed, a suitable implement engaging with the eye *m* of the stopper and drawing the latter in its inverted position from the neck, as shown in Fig. 2, 75 both flanges *b* and *d* being free to yield when the stopper is drawn in this direction, so that they afford no obstacle to the free removal of the stopper from the bottle. The latter can then be cleaned in any of the usual bottle-washing machines, and the stopper can also 80 be readily cleaned prior to reinsertion in a bottle.

While I prefer to form the stopper in the manner shown in Fig. 3, this construction is 85 not absolutely necessary. For instance, the disks *b* and *d* may be separate from each other, the tubular shank *a* being dispensed with and washers *g*, *h* being used in place of the same, that portion of the stem *f* between 90 these washers being flattened, as at *n'*, to form shoulders, which hold the washers in place. (See Fig. 4.) A substitute may also be used for the inner disk, *d*, if desired. For instance, in Fig. 5 I have shown the inner end 95 of the stem *a* bent so as to form a loop, *d'*, the free end of which has a little play, so that in

driving the stopper into the neck of the bottle the loop will be contracted until it has passed the contracted portion of the neck, and will then be free to expand in the flaring 5 lower portion of the neck to form a lock and prevent the removal of the stopper from the neck of the bottle.

It will be observed that in all of the stoppers shown the rigid stem *f* projects some distance above the upper washer, *g*, thus not only providing a ready means of applying the stopper to the plunger of the bottle-filling machine, but also facilitating the pushing of the stopper into the bottle in order to open 15 the same.

The lower disk, *d*, in the stoppers (shown in Figs. 1 and 4) serves as a gas-stop when the bottle contains effervescent liquids; but in the stoppers there shown this latter function 20 is incidental to the main function of the disk, which is that of a lock to prevent displacement of the upper or sealing disk from its proper position in the neck of the bottle.

Having thus described my invention, what I 25 claim, and desire to secure by Letters Patent, is—

1. The combination, in a bottle-stopper, of the stem having an upper flexible disk and a washer above and of slightly smaller diameter than the disk, and having below said disk a lock free to yield on the inward movement of the stopper, but expanding for engagement with the tapering neck after the stopper is inserted, and beyond said lock a 35 portion for engaging with an extractor, whereby the stopper may be withdrawn when inverted, all substantially as specified.

2. The combination, in a bottle-stopper, of a stem having an upper flexible disk and a 40 washer of slightly smaller diameter than the disk, and having below said sealing-disk an

other flexible disk free to yield on the inward movement of the stopper, a washer against which the disk bears to prevent yield in the other direction, and beyond said washer 45 a portion for engaging with an extractor, whereby the stopper may be withdrawn when inverted, all substantially as specified.

3. The combination, in a bottle-stopper, of a tubular shank, having a sealing-disk at the upper end and a locking-disk at the lower end, with a stem passing through said tubular shank and having above the sealing-disk a washer of slightly smaller diameter than the disk, said stem also having below the locking-disk a washer serving as a backing for said disk, and beyond said washer a portion 55 for engaging with an extractor, whereby the stopper may be withdrawn when inverted, all substantially as specified. 60

4. The within-described sealing device for a bottle-stopper, the same consisting of a tubular shank with disks at top and bottom, the whole being of rubber or equivalent flexible material, all substantially as specified. 65

5. The combination of the sealing portion of the stopper, comprising a tubular shank having a sealing-disk at the top and a locking-disk at the bottom, confining-washers at the opposite ends of said shank, and a central stem having an eye at the inner end bearing against the lower washer, and a flattened portion forming shoulders for retaining the upper washer, all substantially as specified. 70

In testimony whereof I have signed my name 75 to this specification in the presence of two subscribing witnesses.

EDWIN L. LLOYD.
